PHOTOGRAPHIC ROLL-FILM

Árpád Barényi, Berlin-Lichterfelde, Germany,
assignor to Voigtländer & Sohn Aktiengesell-
schaft, Brunswick, Germany, a joint-stock
company of Germany

Application October 21, 1933, Serial No. 694,626
In Germany October 31, 1932

1 Claim. (Cl. 95—9)

My invention relates to improvements in photographic roll-films, and more particularly in roll-films in which a strip of gummed paper or the like is attached to the end of the protective 5 backing strip of the sensitized film which is located at the inner end of the film wound on the film delivering spool, the said gummed strip being used for fixing the exposed film in position on the film receiving spool. After the exposed film has 10 been wound on the film receiving spool, and before the gummed strip is applied to the outer convolution of the backing strip of the film for holding the same in position, a part of the end 15 of the backing strip is folded inwardly or torn off so as to expose the coated surface of the strip of paper, and in this operation it happens that the end of the backing strip slips from the hand of the 20 photographer so that the spool is partly unwound and light has access to the sensitized 25 film.

The object of the improvements is to provide a roll-film in which the end of the backing strip having the gummed strip of paper attached thereto may be readily torn off, so that there is no 25 danger of the strip slipping from the hand of the 30 photographer, and with this object in view my invention consists in providing the end of the 35 backing strip with a weakened line disposed transversely of the gummed strip of paper and 40 permitting the end of the backing strip to be readily torn off or folded inwardly so as to expose the gummed strip of paper.

For the purpose of explaining the invention an example embodying the same has been shown in 45 the accompanying drawing in which the same reference characters have been used in all the views to indicate corresponding parts. In said drawing

Fig. 1 shows the tail or inner end of the 50 backing strip and a strip of gummed paper attached thereto, and

Fig. 2 is a sectional elevation showing the film 55 receiving spool having the film and most of the backing strip wound thereon, the outer end of the 60 backing strip being torn off to expose the gummed strip.

To the tail end of the sensitized film 6 a protective 65 backing strip 1 is attached in the usual

way, which backing strip has its end tapered, as is shown at 2, the said tapered end permitting the strip to be inserted in the slit of the spool carrying the sensitized and non-exposed film. To the 70 end of the backing strip a gummed strip 4 of paper or other suitable material is attached at 3, the said strip being coated at its inner side with a suitable adhesive, and lying loose with its outer portion on the backing strip. The end of the 75 backing strip is provided with a weakened, perforated or scored line 5 disposed transversely of and crossing the strip 4 and permitting the end of the 80 backing strip to be readily torn off for exposing the gummed surface of the strip 4.

In Fig. 2 I have shown the film receiving spool 85 7 having the exposed film and most of the backing strip 1 wound thereon and also having the end of the outer end of the backing strip torn off along the weakened line 5, so that the end of the 90 gummed strip of paper 4 is exposed and may be 100 readily fixed to the outer convolution of the backing strip.

I have found that by providing the weakened line 5 the end of the backing strip 2 may be readily torn off without the photographer losing hold 105 of the spool.

I claim:

A roll-film comprising a sensitive strip, a strip 110 of protective backing material of greater length than said sensitive strip, to which said sensitive 115 strip is attached, the tail end of said backing strip, beyond the end of said sensitive strip, being tapered to form a spool-engaging tongue, the said 120 backing strip being weakened on a transverse line 125 spaced at an interval forward of the tip of such 130 tapered tongue, and a gummed securing strip attached at one end to said backing strip at a point 135 forward of such weakened line and extending free 140 and unsecured rearwardly from such point of attachment beyond the weakened line and terminating short of the tail end of the backing strip, 145 whereby when the backing strip with the sensitive strip carried by it has been coiled upon a film-receiving spool and the end of the tapered tongue has been torn away along such weakened line the gummed strip may serve to secure the 150 coil.

ÁRPÁD BARÉNYI.
